(57) **CLAIM**

I claim the ornamental design for a beverage can holder, as shown and described.

DESCRIPTION

FIG. 1 is a side view of a beverage can holder, showing my new design, in a flattened configuration without a beverage container inside it.

FIG. 2 is a front elevational view of the beverage can holder, with a beverage can indicated by dotted lines.

FIG. 3 is a side elevational view of the beverage can holder, with a beverage can indicated by dotted lines.

FIG. 4 is a top view of the beverage can holder, with a beverage can indicated by dotted lines; and,

FIG. 5 is a bottom view of the beverage can holder, with a beverage can indicated by dotted lines.

The beverage can indicated by dotted lines in FIGS. 2, 3, 4, and 5 does not form part of the claimed invention.
